V. M. EXNER

Des. 168,293

AUTOMOBILE LAMP

Filed June 12, 1952

UNITED STATES PATENT OFFICE

168,293

AUTOMOBILE LAMP

Virgil M. Exner, Birmingham, Mich., assignor to
Chrysler Corporation, Highland Park, Mich., a
corporation of Delaware

Application June 12, 1952, Serial No. 20,164

Term of patent 7 years

(Cl. D48—32)

To all whom it may concern:

Be it known that I, Virgil M. Exner, a citizen of the United States, residing in the city of Birmingham, county of Oakland, and State of Michigan, have invented a new, original, and ornamental Design for an Automobile Lamp, of which the following is a specification, reference being had to the accompanying drawings, forming part thereof, in which:

Fig. 1 is a side elevational view of an automobile lamp, showing my new design;

Fig. 2 is a front elevational view thereof; and
Fig. 3 is a rear elevational view thereof.

I claim:

The ornamental design for an automobile lamp, substantially as shown.

VIRGIL M. EXNER.
